UNITED STATES PATENT OFFICE

138,809

DESIGN FOR A PUTTER HEAD

Tracy S. Park, Houston, Tex.

Application June 1, 1944, Serial No. 113,828

Term of patent 14 years

(Cl. D34—5)

To all whom it may concern:

Be it known that I, Tracy S. Park, a citizen of the United States, residing at Houston, in the county of Harris, in the State of Texas, have invented a new, original, and ornamental Design for a Putter Head, of which the following is a specification, reference being had to the accompany drawing, forming a part thereof.

I claim:

The ornamental design for a putter head, as shown.

TRACY S. PARK.
